UNITED STATES PATENT OFFICE.

ETTA W. WHEELOCK, OF NORTH CAMBRIDGE, MASSACHUSETTS, ASSIGNOR,
BY MESNE ASSIGNMENTS, TO SYLVIA W. HUNT AND LILLIAN MAY HUNT,
OF BROOKLINE, MASSACHUSETTS.

SKIRT-HOLDING DEVICE.

SPECIFICATION forming part of Letters Patent No. 726,830, dated April 28, 1903.

Application filed July 23, 1902. Serial No. 116,695. (No model.)

To all whom it may concern:

Be it known that I, ETTA W. WHEELOCK, a citizen of the United States, residing at North Cambridge, in the county of Middlesex and 5 State of Massachusetts, have invented an Improved Skirt-Holding Device, of which the following is a specification.

My invention has for its object to provide a simple and convenient device whereby a 10 dress-skirt may be caught up and properly held at the side of the wearer, thus leaving both hands free.

To this end my invention consists in a detachable skirt-holding device comprising a 15 fob-strap provided with means for attachment to the waistband or belt and a buckle or slide adjustable on said strap and provided with a depending clasp having jaws terminating in pads adapted to be closed upon the 20 gathered folds of the skirt by a sliding ring or other device acting to bring the jaws together.

In the accompanying drawings, Figure 1 is 25 a view of my dress-skirt-holding device, illustrating the manner in which it is applied to a skirt for the purpose of holding up the same.

Fig. 2 is a view of the rear side of the supporting device. Fig. 3 is a front view of the same. Fig. 4 is a rear view of the buckle. 30 Fig. 5 is a rear view of the ornament which is applied to the front portion of the holder.

In the said drawings, A represents a fob-strap, preferably composed of a piece of ribbon, which may be of a color to match that 35 of the dress-skirt with which the holder is to be used, said strap being doubled by passing it through the slotted base-plate 10 of a flat metal hook B, by means of which the holder may be conveniently attached to the waistband or belt of the wearer, as shown in Fig. 1.

C is a buckle or slide mounted upon the rear or inner member or fold 12 of the doubled strap A and preferably made adjustable thereon, said buckle having hinged to its lower 45 edge a clasp or clamp D, preferably composed of a single piece of spring-wire doubled to form a pair of jaws 14 14, each of which terminates in a pad 15, preferably composed of

a metal disk covered with soft cloth or other suitable material of the desired color, thereby 50 avoiding the tearing, injuring, or soiling of the material with which the pads are brought into contact, said jaws being adapted to be closed upon the folds of the skirt to hold the same when gathered up by means of a sliding 55 ring 18, (shown in Fig. 2,) encircling the jaws and held in place when slid down thereover by engaging notches or serrations on the outer sides of the same. The lower portion of the inner member 12 of the strap A overlies and 60 conceals the clasp D, and the outer member 20, which overlies and conceals the buckle C, is preferably provided with an ornamental slide 21, which may be secured in place by 65 stitches passed through its rear bar 22 or in other suitable manner, thereby giving the holder a stylish and finished appearance like that of a watch-fob and also serving as a weight to hold the strap in position when hanging free.

The edges of the inner and outer folds 12 20 are preferably connected together by means of a few stitches on each side at about the location of the ornament 21.

The buckle or slide C, with its clasp D, can 75 be easily adjusted upon the strap A to enable the device to hold the skirt in the exact position desired at the side of the wearer, thus leaving both hands free to carry parcels, umbrella, grip, &c.

The above-described holder possesses the 80 advantages of simplicity and durability and can be readily hooked onto a belt or the waistband of a skirt and as conveniently-detached therefrom when not required for use.

What I claim as my invention, and desire to secure by Letters Patent, is—

1. A skirt-holding device comprising a fob-strap doubled to form an inner and an outer member or fold and provided with a hook at 90 its upper end for attachment to the belt or waistband of the wearer, a buckle mounted upon the inner member of the strap and concealed by the overlying outer member thereof, said buckle being provided at its bottom 95 with a skirt-clasp hinged thereto and consist-

ing of a pair of jaws terminating in pads for contact with the skirt, said clasp being concealed by the lower portion of the inner member of the strap which overlies it, and means 5 for closing said jaws upon the folds of the skirt.

2. As a new article of manufacture, a skirt-support comprising a doubled fob-strap provided on its outer side with an ornamental 10 device to complete the fob-like character of the strap, a suspension device at the bend of the

strap, and a concealed pair of adjustable clamping-jaws on the inner member of the fob-strap; the lower ends of the strap hanging free, substantially as described. 15

Witness my hand this 21st day of July, A.D. 1902.

ETTA W. WHEELOCK.

In presence of—

P. E. TESCHEMACHER,
R. HENRY MARSH.
